Des. 184,880
Patented Apr. 14, 1959

184,880

STRINGING BLOCK

L. E. Lindsey, Pasadena, Calif.

Application January 25, 1957, Serial No. 44,610

Term of patent 7 years

(Cl. D41—1)

Figure 1 is a front elevational view of the stringing block embodying my new design;

Figure 2 is a side view of the design illustrated in Figure 1; and

Figure 3 is a rear elevational view of the design.

I claim:

The ornamental design for a stringing block, as shown.
